UNITED STATES PATENT OFFICE.

HERMAN B. GAFFERS, OF WATERVLIET, NEW YORK.

SCAFFOLD.

Application filed August 18, 1924. Serial No. 732,867.

This invention relates to improvements in scaffolds and more particularly to an improved adjustable leg or rail construction for trestles, ladders, and similar structures.

5 The object of the invention is to provide an improved adjustable leg or rail construction of a simple, strong, durable nature that will be thoroughly reliable and efficient in use.

10 The invention, with other objects and advantages thereof, and the particular construction, combination and arrangement of parts comprising the same, will be understood from the following detailed description, when considered in connection with the accompanying drawing, forming part hereof, and illustrating one embodiment of the invention.

In the drawing:

20 Figure 1 is an end elevation of one of the end supports of a trestle equipped with adjustable legs in accordance with the present invention.

Fig. 1^a is a detail section on the line 1^a—1^a

25 of Figure 1.

Fig. 2 is a detail side elevation, on an enlarged scale, of one of the adjustable legs.

Fig. 3 is a detail front elevation of the adjustable leg construction illustrated in 30 Figure 2.

Fig. 4 is a detail longitudinal section of the construction illustrated in Figure 2, and

Fig. 5 is a transverse section on the line 5—5 of Figure 4.

35 The invention comprehends an adjustable leg construction including a pair of slidably related wooden leg sections, one of said sections having a metal member secured thereto and provided with a series of notches with

40 which cooperates a locking device mounted on the other leg section to hold the leg sections in different positions of adjustment relatively to each other. More particularly the invention contemplates a metal rack member in the form of a flat metal strip seated in a groove in one of the leg sections, and bolts or equivalent means extending transversely of and piercing the leg section and the metal strip member, and securing the parts

45 together.

50 While a specific embodiment of the invention is illustrated in the drawings, it will of course be understood that changes and variations in the particular construction shown and the embodiment of the invention in other forms with various scaffolding

structures, trestles, ladders and the like, as will appeal to those skilled in the art and falling within the scope of the appended claims, may be practiced without departing 60 from the spirit of the invention.

In the particular embodiment of the invention illustrated in the drawings, the same is shown as applied to a trestle structure, one end support of the trestle being shown, by way of example, the same comprising pairs of slidably related upper and lower leg sections 1—2. 3 designates a transverse tie member connecting the upper leg sections 1, and 4 pairs of pins located on the transverse tie member 3 in spaced relation with the lower end portions of the upper leg sections 1 and serving to maintain the lower leg sections 2 in position adjacent the inner faces of the upper leg sections.

55 In accordance with the present invention each of the upper leg sections 1 is provided with a metal rack member in the form of a flat metal strip 5 seated in a groove 6 in the leg section, and secured thereto by bolts and nuts 7—8, or equivalent means, the bolts 7 extending transversely of and piercing the leg sections 1 and the metal strip member 5, see particularly Figure 5 of the drawings, the parts being assembled by inserting the flat metal strip member 5 edgewise into the groove 6, then inserting the bolts 7 through suitable apertures provided in the leg sections 1 and the metal strip 5, and tightly turning up the nuts 8 on the bolts 7. The

60 groove 6 which is located centrally of the edge faces of the leg section, is relatively deep and the metal strip member 5, which is provided with a series of notches 5' is of a width, as shown, so that when seated in the groove 6, the same extends well into the leg section with its series of notches or notched part projecting outwardly from the face thereof. The metal strip member 5 is constructed of steel or other suitable metal.

65 On each lower leg section 2 is a locking device adapted to cooperate with the series of notches 5' of the metal strip member 5 to lock the leg sections in different positions of adjustment. The locking device is shown as a bail 9, said bail having end portions 9' pivotally engaging bearings on brackets 10 secured by screws or other suitable means to the upper portions of the leg sections 2.

70 It will be noted by the special construction and arrangement of parts hereinbefore described that a good anchorage for the metal

rack member 5 is provided and the same is firmly secured to the leg section, while at the same time the leg section is reinforced by the metal strip member, the resulting structure being of a simple, strong, durable nature and easily assembled.

What I claim is:

1. An adjustable leg construction of the class described, including a pair of slidably related leg sections, one of said leg sections being provided with a groove in one side face thereof intermediate its side edges, a member in the form of a flat metal strip having a series of notches along one edge thereof, said member being seated in said groove with its notched portion projecting outwardly beyond the face of the leg, and means securing said metal strip member to the leg section including fastening members extending transversely of said leg section into the same and through the metal strip member, in combination with a movable locking device mounted on the other leg section and adapted to cooperate with the series 25 of notches of the metal strip member.

2. An adjustable leg construction of the class described including a pair of leg sections slideable one upon the other, one of said leg sections being provided with a groove in one side face thereof intermediate its side edges, a member in the form of a flat metal strip having a series of notches along one edge thereof, said member being seated in said groove with its notched part projecting beyond the face of the leg, and means securing the metal strip member to the leg section, said means comprising bolts extending transversely through the leg section and metal strip member from one side to the other of the leg section, and securing nuts on end portions of the bolts at one side face of the leg section, in combination with a movable locking device mounted on the other leg section and adapted to cooperate with the series of notches of the metal strip member.

In testimony whereof I hereunto affix my signature.

HERMAN B. GAFFERS.
